(57) **CLAIM**

The ornamental design for a dispenser cover, as shown and described.

DESCRIPTION

FIG. 1 is a perspective view of a dispenser cover, showing my design;

FIG. 2 is a front elevational view of the dispenser cover, the right elevational view, left elevational view, and rear elevational view being identical.

FIG. 3 is a top view of the dispenser cover; and, FIG. 4 is a bottom view of the dispenser cover.

The broken lines in FIGS. 1, 2 and 3 represent the bounds of the claimed design; the broken lines in FIG. 4 are for illustrative purposes only. None of the broken lines form part of the claimed design.
